UNITED STATES PATENT OFFICE.

CHARLES J. SOSS, OF NEW YORK, N. Y., ASSIGNOR OF ONE-THIRD TO HENRY SOSS AND ONE-THIRD TO SAMUEL SOSS, BOTH OF NEW YORK, N. Y.

HINGE.

1,153,720.

Specification of Letters Patent. Patented Sept. 14, 1915.

Application filed November 3, 1914. Serial No. 870,051.

To all whom it may concern:

Be it known that I, CHARLES J. SOSS, a citizen of the United States, and residing at New York in the county of New York and 5 State of New York, have invented certain new and useful Improvements in Hinges, of which the following is a specification, such as will enable those skilled in the art to which it appertains to make and use the 10 same.

This invention relates to hinges, and particularly to what are known as invisible hinges, and the object thereof is to provide an improved device of this class designed 15 particularly for use in connection with the doors of automobiles and similar vehicles, and the construction and arrangement of which is such that the door may be detached whenever desired for any purpose without 20 detaching that part of the hinge which is connected with the door frame; a further object being to provide a hinge of the class specified which is simple in construction, effective in operation, and which may be 25 used wherever hinges of this class are desired.

The invention is fully disclosed in the following specification, of which the accompanying drawing forms a part, in which the 30 separate parts of my improvement are designated by suitable reference characters in each of the views, and in which:—

Figure 1 is a perspective view of my improved hinge; Fig. 2 a perspective view of 35 one part thereof detached; Fig. 3 a side view of that part of the hinge which is adapted to be connected with the door, part thereof being indicated in dotted lines only; and, Fig. 4 a sectional side view of a portion of that 40 part of the hinge which is adapted to be connected with the door frame.

In the practice of my invention, I provide a hinge of the class specified, comprising in 45 its construction two hinge butts *a* and *b*, and the hinge butt *a*, in practice, is secured to the door frame and countersunk therein in the usual manner, and the hinge butt *b* is secured to the door in the usual manner.

The hinge butt *a* comprises, in the construction shown, a U-shaped box member *a*² having parallel sides *a*³ provided at their free edges with laterally directed wings *a*⁴ having screw-holes *a*⁵ through which are passed screws to secure said part of the 55 hinge to a door frame, and the U-shaped box

member *a*² is open at its opposite sides, in the construction shown, but all sides thereof may be closed, if desired.

The side wings *a*⁴ of the box member *a*² are provided centrally thereof with approximately semi-circular recesses *a*⁶ which open inwardly, and on the inner sides of the recesses *a*⁶ the sides *a*⁸ of the U-shaped box member are provided with laterally directed ears *a*⁷ which are cut from the material of said wings as shown and are provided with screw-holes *a*⁸, and the ears *a*⁷ close the recesses *a*⁶ on the inner sides of the wing *a*⁴.

The butt *a* is stamped from sheet metal and the recesses *a*⁶ and ears *a*⁷ are similarly 70 formed, and in this operation the ears *a*⁷ are elongated so that they overlap the outer walls of the recesses *a*⁶ as shown at *a*⁹, but this overlapping of the ears *a*⁷ of the wings *a*⁴ at the outer ends of the recesses *a*⁶ is not 75 absolutely essential.

The hinge butt *b* comprises the usual plate *b*², and this plate is provided centrally of its outer side with an L-shaped arm *b*³, and the free end portion *b*⁴ of the arm *b*³ is provided with a pivot pin hole *b*⁵. In the construction shown the hinge butt *b* with its arm *b*³ is composed of two separate similar parts stamped from sheet metal and secured together by spot welding, forging or in any 80 other way, and each of these parts involve the plate member *b*² and a part of the arm *b*³. I also provide a supplemental hinge member *c* which comprises a U-shaped box part having parallel side plates *c*² provided 85 at their free edges with laterally directed ears *c*³ adapted to enter the recesses *a*⁶ and having screw-holes *c*⁴, and the side plates *c*² are provided at one corner of their free edges with similar inwardly directed lugs *c*⁵ 90 and the part *c* is also stamped from sheet metal.

In assembling the parts of this hinge the L-shaped arm *b*³ of the butt *b* is inserted between the side plates *c*² of the part *c*, and 100 said parts are connected by a pivot pin passed through the hole *b*⁵ in the arm *b*³ and through corresponding holes *c*⁶ in the side plates *c*² of the part *c*, and while the part *c* actually forms a part of the butt *b*, 105 it is, in practice, secured to the butt *a* by means of screws *d*. After the part *c* has been connected with the arm *b*³ of the part *b* in the manner described, said part *c* is inserted into the hinge butt *a* as shown in Fig. 110

1, and in this operation the ears c^3 of the part c enter the recesses a^6 and the screws d are passed through the screw-holes c^4 and the screw-holes a^8 , and the hinge is ready 5 for use. When the hinge butt a has been secured in the door frame and the hinge butt b to the door, the door may be detached whenever desired by simply removing the screws d , and the hinge butt a will remain in 10 firm connection with the door frame, and the separate parts of the hinge may be again connected and the door secured in position by inserting the part c into the hinge butt a and securing it by the screws d as shown and 15 described, and in the operation of opening and closing the door the inwardly directed lugs or projections c^6 of the part c limit the outward movement of the door, as will be readily understood, in which operation the 20 arm b^3 comes in contact with said lugs or projections.

The general form and arrangement of the parts of this hinge are old, the novel features being found in the ears a^7 of the part 25 a which close the inner sides of the recesses a^6 and into which the screws d are passed for securing the part c to the part a , and said ears a^7 form washers integral with the part a and while said ears are shown and 30 described as connected with the side walls of members of said part this is not absolutely necessary, and said ears may be formed in connection with the side wings a^4 of said part, if desired.

35 Having fully described my invention, what I claim as new and desire to secure by Letters Patent, is:—

1. In a hinge, a part adapted to be secured in a stationary support, said part being 40 stamped from sheet metal and comprising a box-shaped portion having parallel side portions provided with free edge portions forming laterally directed wings in which are formed recesses back of which are ears

cut from the material of said wings and 45 integrally connected with said side portions and provided with screw holes and the length of which is greater than the length of said recesses.

2. A hinge of the class described, comprising a part adapted to be secured in a door frame and a part adapted to be secured to a door, the part which is adapted to be secured in the door frame comprising a box portion having parallel sides provided with 55 free edges having laterally directed wings provided with recesses inwardly of which are ears provided with screw-holes, and the part which is adapted to be secured to the door frame being provided with an L-shaped 60 arm, a supplemental part adapted to be secured in the part which is adapted to be secured in the door frame in which the L-shaped arm is pivoted, said supplemental part comprising parallel side plates having 65 free edges provided with laterally directed ears adapted to enter said recesses and provided with screw-holes, said side plates being also provided at one of their free edges with inwardly directed lugs. 70

3. In a hinge, a part adapted to be secured in a stationary support, said part being stamped from sheet metal and comprising a box-shaped portion having parallel side portions provided with free edge portions 75 forming laterally directed wings in which are formed recesses back of which are ears cut from the material of said wings and integrally connected with said side portions and provided with screw holes. 80

In testimony that I claim the foregoing as my invention I have signed my name in presence of the subscribing witnesses this 2nd day of November, 1914.

CHARLES J. SOSS.
